UNITED STATES PATENT OFFICE

153,367

DESIGN FOR A RAIL VEHICLE

Otto A. Kuhler, Blauvelt, N. Y., assignor to American Car and Foundry Company, New York, N. Y., a corporation of New Jersey

Application January 24, 1947, Serial No. 136,399

Term of patent 14 years

(Cl. D66—1)

To all whom it may concern:

Be it known that I, Otto A. Kuhler, a citizen of the United States, residing in Blauvelt, in the county of Rockland, State of New York, have invented a new, original, and ornamental Design for a Rail Vehicle, of which the following is the specification, reference being had to the accompanying drawings and which form a part thereof.

Fig. 1 represents a side elevational view of the rail vehicle, Fig. 2 a top plan view of the rail vehicle, and Fig. 3 is an end view of the rail vehicle.

The side of the rail vehicle opposite that shown in Fig. 2 is the same as illustrated and the end opposite that shown in Fig. 3 is the same as illustrated.

The present design comprises as the principal and dominating feature thereof the portions as shown in full lines on the accompanying drawings.

I claim:

The ornamental design for a rail vehicle, substantially as shown and described.

OTTO A. KUHLER.
